UNITED STATES PATENT OFFICE.

DENNIS FRANCIS CROWLEY, OF FORT LEAVENWORTH, KANSAS,

HYDROCARBON-GAS GENERATOR AND BURNER FOR CRUDE PETROLEUM.

SPECIFICATION forming part of Letters Patent No. 735,472, dated August 4, 1903.

Application filed February 13, 1902. Serial No. 83,913. (No model.)

To all whom it may concern:

Be it known that I, DENNIS FRANCIS CROWLEY, a citizen of the United States, residing at Fort Leavenworth, in the county of Leavenworth and State of Kansas, have invented new and useful Improvements in Hydrocarbon-Gas Generators and Burners for Crude Petroleum, of which the following is a specification.

My invention relates to hydrocarbon-gas generators, and the object of my invention is to provide a suitable generator for vaporizing crude petroleum and which is especially adapted for boiler-furnaces.

I will proceed to describe my invention with reference to the accompanying drawings, in which—

Figure 1 is a front elevation of my invention applied to an upright boiler, a part of the boiler and the pit-pan being in section. Fig. 2 is a top plan view of the jet-burner pipes detached. Fig. 3 represents one of the turns of either of the generator-coils broken away.

The generator proper comprises a main coil 1, a shorter coil 2, and a pit-pan 3. The pan 3 is set in the ash-pit and contains a layer of asbestos 3'. The upper end of the main coil 1 is connected by a pipe 5 to the oil-tank 4. It will be noticed that pipe 5 descends from the tank 4, then ascends, thereby forming a trap for impurities which may become separated from the oil by reason of their greater weight. The jet-burner pipes 21 are concentric and circular, as shown in Fig. 2, and the outer of said pipes rests on the grate-bar flange, as shown, (the grate being removed.) One of the pipes 21 is connected by pipes 15 16 to the lower end of the main coil 1. The circular pipes 21 are connected together by several radial pipes 21, as shown in Fig. 2. In the upper portions of all the pipes 21 are a large number of perforations or jet-burners 22, through which the gas issues during the operation of the generator. The aforesaid pipe 15 extends beyond its connection with coil 1 horizontally upon the asbestos 3' and terminates in a burner 17. The upper end of the shorter coil 2 is connected by a pipe 13 to pipe 5. In pipe 13 is a hand-valve 10. The lower end of coil 2 is connected to a pipe 20, which lies horizontally

upon the asbestos 3' and extends upwardly and then horizontally underneath the jet-burner pipes 21. In the upper horizontal portion of this pipe 20 are several openings or burners 20', the purpose of which is to ignite the jet-burners 22, as described hereinafter. Connected to the horizontal portion of pipe 20, which lies in the pan 3, are two burners 18 19 under the respective coils 1 and 2. A priming-pipe 14 is connected to pipe 5 and extends into the pan 3. In this pipe 14 is a hand-valve 11. The sides of the pan 3 are perforated, as at 3", for the purpose of admitting an adequate supply of air to the burners 18 19. In pipe 5 are two hand-valves 6 and 7. The former controls the supply of oil to both of the coils 1 2. The latter is used as described hereinafter. In pipe 5 near valve 7 is a valve 9, having an arm 8, which is connected by a rod 23 to a lever 24, which is connected to a diaphragm in a steam-chamber 25, connected to the boiler by a tube 26. The chamber 25 and the diaphragm are of the usual and well-known construction. On lever 24 is a weight, (not shown,) which opposes the pressure of steam upon the diaphragm. The valve-arm 8 is so adjusted that when the steam-pressure rises in the boiler the valve 9 will be partially closed, thereby diminishing the supply of oil to the main coil 1.

The operation is as follows: To start up, first open valve 6, then open valve 11. This admits oil into the pan 3. When the asbestos 3' is saturated or covered, close valve 11 and ignite the oil in the pan. Before this oil has entirely burned out open valve 10, which admits oil to coil 2. The gas generated in said coil will pass to burners 18 and 19 and to pipe 20. Burners 18 and 19 will be ignited by the flame rising from the oil in the pan 3. Burner 18 will heat coil 1, while burner 19 will maintain the heat of coil 2. Ignite the jets 20' in pipe 20 with a torch. Open valve 7. The automatic valve 9 being open, oil will flow into the main coil 1 and be vaporized. This vapor will rise through pipe 15 and will fill the jet-burner pipes 21, issuing through perforations 22. These jets will be ignited by the jets 20' from pipe 20. The boiler is heated by the jets rising from pipes 21. Vapor from coil 1 will also traverse the lower branch of pipe 5 and issue through burner 17 and will be ig-

nited by the flame of burner 18. When said jets are ignited, the coil 2 is not needed and valve 10 may be closed. If it be desirable to let the steam down for a short time only, close 5 valve 7 and open valve 10. This will admit oil to coil 2 and will shut off the supply from coil 1. Burners 18 and 19 will be ignited from burner 17, and when the vapor enters pipe 20 the jets from perforations 20' will be ignited from some 10 of the jets from pipes 21. Thus the coil 1 will be kept hot by burner 18. To ignite the jets from pipes 21, open valve 7 and the vapor generated in coil 1 will be ignited by the jets from pipe 20, while burner 17 will be ignited 15 from burner 18. When the jet-burners 22 are burning with full force, coil 2 is not required (as already stated) and therefore valve 10 may be closed. Coil 1 being kept hot by its own burner 17 will generate sufficient gas 20 to supply the jet-burners 22; but if it is desired to "turn down" the jet-burners 20 valve 7 is closed, which cuts off the main coil 1, and valve 10 is opened, which readmits oil to coil 2. The flame still rising from burner 17 will 25 ignite burners 18 and 19 and burner 19 will heat up coil 2, which will begin to vaporize the oil when sufficiently heated. Coil 1 will be kept hot by burner 18, so that when a hot fire is again required coil 1 will be ready to 30 generate gas for that purpose.

Each coil 1 and 2 is preferably made of

unions 28 and nipples 29, as shown in Fig. 3. Each union 28 has a screw-plug 31 therein to confine the vapor and cause it to traverse the entire coil. By removing the plugs 31 the 35 interior of the pipes and unions may readily be cleaned out when necessary.

Having now fully described my invention, what I claim as new, and desire to secure by Letters Patent of the United States, is—

In a heating apparatus for burning crude petroleum, two circular jet-burner pipes lying in the same horizontal plane, one within the other, said pipes being perforated, radial pipes connecting said pipes together, a perforated igniter-pipe subjacent to said jet-burner pipes, a main generator-coil below and connected to said jet-burner pipes, a burner 17 below and connected to said generator-coil, a shorter generator-coil adjacent to the main 50 generator-coil, two burners 18 and 19 connected to said shorter coil, said burners being below said coils, respectively, a connection between said shorter coil and said igniter-pipe, substantially as described.

In testimony whereof I affix my signature in the presence of two witnesses.

DENNIS FRANCIS CROWLEY.
